[57]

ABSTRACT

A transparent plastic slide having a plurality of covered examination chambers defined between generally parallel and uniformly spaced sidewalls integral with the slide, to hold specimen liquid in layers of substantially uniform depth for examination. Each chamber is formed as a laterally opening pocket having a semi-circular edge wall and an open side facing toward one edge of the slide, and a channel extends from each open side to the edge of the slide. The sidewalls are sufficiently close together to cause specimen liquid to be drawn into, and to fill, the chamber by capillary action when a quantity of the liquid is placed in the channel at the open side, such capillary action being sufficient to hold the liquid in the chamber when the edge of the slide is tapped gently against a suitable surface to remove excess liquid from the channel.

TRANSPARENT SLIDE FOR THE EXAMINATION OF LIQUID SPECIMENS

BACKGROUND OF THE INVENTION

This invention relates to the examination of liquid specimens, and relates more particularly to an improved transparent slide for receiving a specimen to be examined, spreading the specimen into a thin film, and holding the specimen as it is subjected to optical examination.

Such slides are used in the examination of a variety of different chemical and biological substances, examples of those most frequently examined being urine, spinal fluid, sputum and blood. In the past, the customary practice has been to place a small quantity of the liquid on a flat, transparent slide plate, and to press a flat, transparent cover plate, called a "cover slip," over the specimen. The cover slip spreads the specimen into a thin film, which is confined between the plate and the slip to facilitate handling with minimum danger of contamination of the specimen or contact thereof with the examining technician.

A principal purpose of this procedure is to prepare the specimen for so-called "wet mount" examination, permitting quantitative microscopic analysis of particulate matter in the liquid. When the specimen has been spread to a film of generally uniform thickness, the technician is able to count the number of solid particles, cells and the like in a given area of the specimen, and this count is indicative of the content of the specimen per unit of volume thereof. It will be apparent, however, that the actual volume of liquid confined beneath a given area of the cover slip is dependent upon several variables, most notably the size of the drop of liquid applied to the slide plate, in the area of the cover slip, viscosity of the liquid, the force applied in squeezing the slip against the plate, and the flatness of the slip and the plate.

All of these factors cooperate in determining the thickness of the film in the area being examined, and thus the actual volume being examined. In addition, the distribution of solid particles in the specimen, particularly larger particles, can be affected by the squeezing action, and slippage can occur between the cover and the slip, with further possible adverse affects on the accuracy of the examination results.

Another limitation of conventional wet mount slides is that it is generally impractical to apply more than one, or at most two, specimens to a single slide of the usual size, because of the danger of intermixing of specimens, and resulting contamination, during uncontrolled spreading thereof into films. An effort has been made to provide a compartmented slide with a plurality of open-sided chambers defined between spaced transparent walls, but the experience with such slides has been less than completely satisfactory, primarily because of the inability of such chambers to confine the specimen effectively against escaping through the open sides thereof when the slide is horizontal, and thus failing to maintain each chamber completely filled during the examination.

SUMMARY OF THE INVENTION

The present invention resides in an improved transparent slide for holding at least one liquid specimen, and preferably several, for wet mount examination, and maintaining each specimen in a thin film of a prese-

lected, substantially uniform depth during examination, so as to make possible uniformly high quality examination. Moreover, the improved slide facilitates the insertion and measuring of standard amounts of the liquid to be examined, and the separation and removal of any excess, all in a rapid and simple manner, while virtually eliminating any possibility of introducing inaccuracies through the redistribution of particles or of intermixing of separate specimens on the same slide, and may be made relatively inexpensively so as to be disposable after use.

More specifically, and as embodied in the preferred mode of the invention shown herein for purposes of illustration, the improved slide has at least one open-sided specimen chamber that is defined between two substantially parallel sidewalls that are sufficiently close together to effect filling of the chamber with the specimen through the open side thereof. Thereafter, the liquid so retained in the chamber, by capillary action, that is, by the attraction of the molecules of the liquid for each other and for those of the solid material forming the walls of the chamber. The sides of the chamber other than the open side are closed by an edge wall which extends between the two sidewalls, the edge wall preferably being curved to promote rapid and even filling of the chamber.

One of the sidewalls (the lower sidewall in use), and the opposite end portions of the edge wall extend beyond the open side of the chamber to define an open-ended entry channel, for receiving a quantity of the liquid to be examined at the open side of the chamber and guiding the liquid into the chamber. After the chamber has been filled, any excess remaining in the channel can be removed by gently tapping one edge of the slide, the edge toward which the open side of the chamber faces, against a paper towel or the like. The specimen is effectively held in the chamber by capillary action during such tapping.

For proper entry and retention of the specimen, the material used for the slide should have high "wettability" and the spacing of the sidewalls should be within a range of 0.004 to 0.020 of an inch, for the liquids customarily subjected to wet-mount examination. Optimum entry and retention is obtained with spacing in the range of 0.006 to 0.012 of an inch, and preferably from 0.009 to 0.010. To insure complete and even filling of the chamber, it should be of smoothly curved configuration so as to avoid corners where air would likely be trapped.

When a plurality of specimen chambers are provided in a single slide (for example, five), they preferably are uniform in area as well as in depth and may be arranged in longitudinally spaced relation with all of the open sides of the chambers facing in the same direction, the inner ends of the chambers adjacent one edge of the slide, and parallel entry channels extending across the slide to the opposite edge thereof. Drops of liquid placed in the channels at the open sides of the chambers will flow immediately into the chambers, and, after the excess remaining is removed by tapping one edge of the slide, all of the specimens can be examined. When the areas and depths, and thus volumes, of the chambers are standardized, as may be readily achieved with the slide of the invention, the results of the examinations also are standardized and can be compared advantageously, even if made by different technicians or at different times.

If desired, one side wall of each chamber can be marked with grid lines for use in indicating different examination fields. The open sides of the chambers can be sealed with wax or the like to preserve the specimens for later use, or the slide can be discarded after the examination has been completed.

Other aspects and advantages of the invention will be apparent from the following detailed description, taken in conjunction with the accompanying drawings.

BRIEF DESCRIPTION OF THE DRAWINGS

FIG. 1 is a perspective view of a slide having a plurality of examination chambers embodying the novel features of the present invention;

FIG. 2 is an enlarged plan view of the slide;

FIG. 3 is a further enlarged longitudinal cross-sectional view taken along line 3-3 of FIG. 2; and

FIG. 4 is a further enlarged cross-sectional view taken along line 4-4 of FIG. 3.

DETAILED DESCRIPTION

Shown in the drawings for purposes of illustration is an improved slide 10 which is formed as an elongated rectangular plate of thin and relatively stiff transparent material, and has a plurality of chambers 11 spaced apart longitudinally of the plate in the central portion thereof to receive and hold liquid specimens that are to be examined. In typical use, a small quantity of liquid is placed in each chamber, or in any desired number of chambers, and the slide is placed under a microscope for a visual examination, such as the analysis of sediment contained in urine.

Each chamber 11 is formed as a thin, flat pocket in the slide plate that is defined between the planes of the flat upper and lower surfaces 12 and 13 of the plate by spaced sidewalls 14 and 15 that are generally parallel to each other and to the upper and lower surfaces of the plate. One side of each chamber is open, and faces laterally toward one longitudinal edge 17 of the plate, and the remainder of the chamber is closed by an edge wall 18 extending around the chamber from one end of the open side to the other.

Because the spacing between the sidewalls 14 and 15 is substantially uniform in all areas of each chamber 11, the depth of a layer of liquid filling chamber also is substantially uniform. Thus, a microscopic count of particles in a given area of a chamber will provide a more accurate and reliable indication of the content of the liquid than was possible with a conventional slide and cover slip.

To facilitate the insertion of liquid in the chambers 11, recesses 19 are formed in the upper surface 12 beside the open sides of the chambers, and extend laterally therefrom toward the longitudinal edge 17 of the plate. Herein, these recesses are channels of rectangular cross-section, the bottom of each channel being a co-planar extension of the bottom sidewall 15 of the associated chamber, and forming a supporting surface for assisting in the introduction of specimen liquid into the chamber. The side edges 20 of the channel similarly are parallel extensions of the opposite end portions of the edge wall 18, and extend all the way to the edge 17 of the plate. Accordingly, each channel 19 opens at one end into a chamber 11, beneath a free edge 21, of the top sidewall 14 thereof, and opens at the other end through the edge of the plate.

In accordance with an important aspect of the present invention, the sidewalls 14 and 15 of each chamber 11 are sufficiently close together to effect filling of the chamber with the specimen liquid through the open side thereof and thereafter to retain the liquid in the chamber, both by capillary action which acts to draw the liquid into the chamber and to hold the liquid securely therein. Thus, liquid placed in a channel 19 at the open side of a chamber will be drawn into, and will completely fill, the chamber when the slide is horizontal, or even if it should be positioned with the channels inclined downwardly to some extent from the chamber openings. When excess liquid is removed by tapping the edge 17 gently against a suitable surface, capillary action retains the liquid in the chambers.

Different shapes may be used for the chambers 11, the edge walls 18 being shown herein in the preferred shape, which is semi-circular in horizontal cross-section. This regular and smooth configuration of the edge walls assists capillary action in producing a smooth flow of liquid, and in insuring that the chambers will be completely filled.

In addition to effective capillary action, a factor to be considered in determining the size of the chambers 11 is the maximum size of particles to be counted in the specimens. The open sides should not be so narrow as to trap larger particles, thereby effectively removing them from the specimens to be studied. Of course, the chambers should not be so deep that capillary action will not be effective to draw in the liquid and fill the chambers. The range of acceptable spacing for the top and bottom walls 14 and 15 is between 0.004 and 0.020 of an inch, and the optimum range is 0.006 to 0.012 of an inch, about 0.010 (± 0.001) being the recommended and preferred spacing of the sidewalls at the opening.

While the slide 10 may be formed in various ways, for example, as a laminate of multiple layers, it preferably is injection molded in a single, integral piece, and is composed of plastic having the desired transparency and "wettability." The preferred plastics are somewhat hygroscopic, and include cellulose ester compositions such as cellulose acetate and cellulose acetate butyrate, sold under the trademark "Tenite" by Eastman Chemical Products, Inc.

When the slide 10 is injection molded, separation of a slide from the dies is facilitated by a slight intentional divergence of the top and bottom sidewalls 14 and 15 toward the open side of each chamber 11, for example, with one sidewall inclined at an angle on the order of three degrees relative to the other. Although this divergence slightly reduces the depth of the inner end portions of the chamber, its effect is negligible, as long as uniformity is otherwise maintained within close tolerances. In any event, the intentional variation is known, and can be taken into consideration in drawing conclusions with respect to an examination of a particular area of a chamber.

The illustrative slide 10 has five individual chambers 11 and can be made in a standard size of one inch by three inches by one-sixteenth of an inch, with each chamber about three-eighths of an inch wide, and three-sixteenths of an inch in radius. The chamber 11a adjacent the right end of the slide in FIG. 2 is shown with a top sidewall 14 that has grid lines for demarking different areas of the chamber. Such grid lines may be

applied to all of the chambers, or none of them, as desired.

From the foregoing, it will be apparent that the present invention provides an improved slide 10 having one or more examination chambers 11 of controlled and substantially uniform depth for receiving and effectively holding quantities of liquid to be examined, thereby eliminating the uncontrollable variables inherent in the use of conventional slides and cover slips. This is achieved in a relatively inexpensive and very effective manner by defining each chamber between generally parallel walls 14 and 15 that are sufficiently close together to effect both the complete filling of the chamber and the retention of the liquid therein by capillary action, which is enhanced by the smooth curvature of the edge wall 18, and the convenience of using the slide is further enhanced by the provision of the channels 19 for introducing the liquid and removing any excess.

It also will be apparent that, while a preferred embodiment has been shown and described, various modifications can be made without departing from the spirit and scope of the invention.

I claim:

1. A slide for use in the examination of liquid specimens of urine, spinal fluid, sputum, blood or the like, said slide comprising:

an elongated rectangular plate of thin and relatively stiff transparent plastic having flat upper and lower surfaces;

a plurality of examination chambers spaced apart longitudinally of said plate in the central portion thereof and each having an open side spaced a substantial distance from, and facing toward, one longitudinal edge of the plate, each of said chambers being defined by top and bottom sidewalls that are generally parallel to each other and to said upper and lower surfaces, and a semi-circular edge wall between said sidewalls and extending around the chamber from one end of said open side to the other end thereof, said sidewalls and said edge wall being integral with said plate;

an open-topped channel extending from each of said open sides across the plate to said one longitudinal edge thereof, and defined by extensions of said bottom sidewall and the opposite end portions of said edge wall, said top sidewalls having free edges overlying said open sides of said chambers; and the spacing of said sidewalls being substantially uniform and within the range of 0.004 to 0.020 of

5

an inch, whereby specimen liquid placed in a channel at the open side of a chamber will be drawn into and held in the chamber by capillary action, and excess liquid can be removed from the channel by tapping said longitudinal edge gently against a surface without removing the liquid from the chamber.

2. A slide as defined in claim 1 wherein said spacing of said sidewalls at said open side is within the range of 0.004 to 0.012 of an inch.

3. A slide as defined in claim 1 wherein said slide is of a one-piece plastic molding with said top walls, said sidewalls and said edge wall integral with the remainder of the slide.

4. A slide for use in the examination of liquid specimens, said slide comprising:

a thin flat plate having flat side surfaces; at least one examination chamber defined in said plate as a thin, flat pocket having an open side spaced a substantial distance from, and facing toward, one edge of said plate, said chamber being defined between two generally parallel and uniformly spaced sidewalls formed by said plate, and an edge wall extending between said sidewalls, at least one of said sidewalls being transparent; one of said sidewalls having a free edge overlying said open side, and the other of said sidewalls extending beyond said open side to said one edge and forming a supporting surface for receiving a quantity of specimen liquid to be examined; and the space between said sidewalls being within the range of 0.004 to 0.020 of an inch and sufficiently narrow to cause the liquid to be drawn into and held in the chamber by capillary action.

5. A slide as defined in claim 4 wherein said edge wall is smoothly curved around said chamber.

6. A slide as defined in claim 5 wherein said plate is of elongated rectangular shape, and a plurality of identical examination chambers are formed in said plate in longitudinally spaced relation thereon, with a channel extending from the open side of each chamber to said edge, the extension of said other sidewall of each of said chambers forming the bottom of a channel.

7. A slide as defined in claim 4 wherein said plastic is a type having high wettability.

8. A slide as defined in claim 4 wherein said sidewalls diverge slightly at a preselected angle toward said open side.

[57]

ABSTRACT

A transparent plastic slide having a plurality of covered examination chambers defined between generally parallel and uniformly spaced sidewalls integral with the slide, to hold specimen liquid in layers of substantially uniform depth for examination. Each chamber is formed as a laterally opening pocket having a semicircular edge wall and an open side facing toward one edge of the slide, and a channel extends from each open side to the edge of the slide. The sidewalls are sufficiently close together to cause specimen liquid to be drawn into, and to fill, the chamber by capillary action when a quantity of the liquid is placed in the channel at the open side, such capillary action being sufficient to hold the liquid in the chamber when the edge of the slide is tapped gently against a suitable surface to remove excess liquid from the channel.

THE PATENT IS HEREBY AMENDED AS
INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS
BEEN DETERMINED THAT:

Claims 1-8 are cancelled.

New claim 9 is added and determined to be patentable.

9. *A slide for use in the examination of liquid specimens, said slide comprising:*
a thin flat plate having flat side surfaces;
at least one examination chamber defined in said plate
as a thin, flat pocket having an open side spaced a
substantial distance from, and facing toward one edge
of said plate, said chamber being defined between two
generally parallel and uniformly spaced sidewalls
formed by said plate, and an edge wall extending
between said sidewalls, at least one of said sidewalls
being transparent and wherein said sidewalls diverge
slightly at a preselected angle toward said open side;
one of said sidewalls having a free edge overlying said
open side, and the other of said sidewalls extending
beyond said open side to said one edge and forming a
supporting surface for receiving a quantity of specimen
liquid to be examined;
and the space between said sidewalls being with the
range of 0.004 to 0.020 of an inch and sufficiently
~~narrow~~ cause the liquid to be drawn into and held
in the chamber by capillary action.
